VACUUM FILLING MACHINE

Dominic W. Tiano, Weymouth, and Arthur F. Whitehead, Quincy, Mass., assignors to Pneumatic Scale Corporation, Limited, Quincy, Mass., a corporation of Massachusetts

Application July 6, 1955, Serial No. 520,216

13 Claims. (Cl. 141—7)

This invention relates to vacuum operated container filling apparatus.

The invention has for an object to provide novel and improved vacuum filling apparatus for filling containers and particularly bottles wherein provision is made for purging the empty bottles with an inert gas in a novel, superior and economical manner immediately prior to the vacuum filling operation whereby to reduce to a minimum the air content of the subsequently filled bottles.

With this general object in view and such others as may hereinafter appear, the invention consists in the vacuum filling machine and in the various structures, arrangements and combinations of parts hereinafter described and particularly defined in the claims at the end of this specification.

In the drawings illustrating the preferred embodiment of the invention:

Fig. 1 is an end view partly in cross section of a bottle purging and filling machine embodying the present invention;

Fig. 2 is a detail view partly in cross section of a portion of the purging and filling mechanism shown in Fig. 1 illustrating the bottles in an elevated position;

Fig. 3 is a detail view partly in cross section illustrating the check valve shown in Fig. 2 in a different position of operation;

Fig. 4 is an end view of the apparatus partly in cross section and illustrating the driving mechanism;

Fig. 5 is a front view partly in cross section showing the driving mechanism as viewed from the left hand side of Fig. 4;

Fig. 6 is a detail view illustrating the mounting of the vacuum control valve and the inert gas control valve relative to their respective manifolds shown in Fig. 1;

Fig. 7 is a cross sectional detail view of a pneumatically operated valve, shown in its closed position, for controlling the supply of the inert gas;

Fig. 8 is a view similar to Fig. 7 showing the inert gas control valve in its open position;

Fig. 9 is a cross sectional view of a pneumatically operated pilot valve forming a part of the pneumatic control mechanism to be described, the valve being shown in its closed position;

Fig. 10 is a view similar to Fig. 9 showing the pilot valve in its open position;

Fig. 11 is a cross sectional detail view of a pneumatically operated vacuum control valve forming a part of the purging mechanism and shown in its closed position;

Fig. 12 is a view similar to Fig. 11 showing the vacuum control valve in its open position;

Fig. 13 is a cross sectional detail view of a vacuum control valve for controlling the vacuum during the filling operation, the valve being shown in its closed position;

Fig. 14 is a view similar to Fig. 13 showing the vacuum control valve in its open position;

Fig. 15 is a cam diagram illustrating the timing of the valves during the purging operation;

2

Fig. 16 is a piping diagram illustrating the pneumatic control mechanism for controlling the purging operation;

Fig. 17 is a piping diagram illustrating the pneumatic control mechanism for controlling the filling operation; and

Fig. 18 is a cam diagram illustrating a modified form of timing of the valves for controlling the purging operation.

In general the present invention contemplates a vacuum filling machine having purging apparatus for purging the empty containers with an inert gas, such as nitrogen, to reduce to a minimum the air content of the containers immediately prior to the vacuum filling operation. The present machine may be used with advantage in filling containers with those liquid food products which are particularly susceptible to contamination upon prolonged exposure to air. The invention is herein illustrated as embodied in a straight line vacuum filling machine of the type illustrated and described in the United States patent to Newey, No. 1,977,138, which is adapted to fill a plurality of bottles in a row simultaneously, and in accordance with the present invention provision is made for first subjecting a row of empty bottles to vacuum to evacuate substantially all of the air therein, and then introducing an inert gas into the bottles to mix with and dilute the remaining air in the evacuated bottles immediately prior to the vacuum filling operation whereby the subsequently filled bottles will be substantially devoid of air. During the vacuum filling operation the inert gas-air mixture is evacuated and replaced with the filling material. In practice the entire upper portion of the machine is preferably hooded and charged with nitrogen gas to provide an atmosphere of inert gas around the bottles during the conveying, purging and filling operations, and in accordance with another feature of the present invention provision is made for modifying the action of the filling mechanism at the end of the vacuum filling operation to prevent excessive evacuation of the gas within the hood through the vacuum filling nozzles when the latter are removed from sealing engagement with the bottles.

Referring now to the drawings which illustrate the different features of the apparatus as embodied in a machine for automatically purging and filling bottles, 10 represents a bottle supporting and elevating member which in the illustrated machine is adapted to operatively support a plurality of rows of bottles to thereby permit the bottles in one row to be purged by an inert gas while the bottles in a succeeding row are being filled. 50 The machine is further provided with a row of purging nozzle units 12 and a row of filling nozzle units 14, and provision is made, as will be described, for elevating the bottle supporting member at the proper time in the cycle of operation of the machine to present the bottles into operative engagement with said nozzle units to enable the purging and filling operations to be performed. Provision is preferably made for feeding the bottles to be purged and filled into the machine upon an incoming conveyor comprising a link belt 20 and for discharging 55 the filled bottles from the machine upon a discharge conveyor 21.

In operation the empty bottles are deposited on the belt 20 and are carried along by the belt until they reach a stop 22, see Fig. 4, adjustably supported upon an upright member 24 forming a part of the machine frame. The link belt 20 runs over an idler sprocket (not shown) at one end of the machine and over a driving sprocket 28 at the other end of the machine. As shown in Figs. 4 and 5, the driving sprocket 28 is fast on a shaft 30 driven by mechanism including a sprocket 32 fast on the shaft 30, a chain 34 and a sprocket 36 which turns free on a stud 38 supported in bracket 39. The sprocket 36

is provided with a bevel gear 40 attached thereto and arranged to mesh with a bevel gear 42 attached to a worm wheel 43, and provision is made for continuously driving the worm wheel 43. As herein shown, the worm wheel 43 is driven from a motor 45 supported upon a platen 47 forming a part of the machine frame, through a belt 48 and pulley 49 fast on a shaft 53. The shaft 53 is provided with a worm 51 which drives the worm wheel 43, the latter being fast upon a cam shaft 52. In this manner a continuous motion is imparted to the conveyer belt 20 to thereby move the empty bottles into a position in which the first bottle rests against the stop 22 while the machine is running.

Provision is made for transferring a plurality of the bottles from their position on the incoming conveyer belt 20 onto the bottle supporting member 10 when the latter is in its depressed position with its surface flush with the surface of the conveyer belt 20 as shown in Fig. 1. As herein shown, provision is made at each cycle of operation for thus transferring a number of bottles corresponding to the number of purging and filling nozzle units 12 and 14 respectively, and during the operation of the machine the transfer of empty bottles from the incoming conveyer belt 20 to the bottle supporting member 10 operates to transfer the previously purged row of bottles from a position under the purging nozzle units 12 into a position under the filling nozzle units 14, and simultaneously to effect the transfer of the filled bottles from a position under the filling nozzle units 14 onto the discharge conveyer 21.

As herein shown, the bottle pushing mechanism comprises a bar 58 mounted on a slide 60 guided in brackets 62 mounted on the platen 47 of the machine. The slide 60 has a reciprocating motion imparted to it by a cam 64 which operates on a lever 66 through a cam roll 68 carried by the cam lever 66. The lever 66 is rockingly mounted on a rocker shaft 50, and the upper end of the cam lever 66 has a forked end 72 which embraces a roll 74 free on a stud 76 fastened in a plate 78 adjustably clamped to a bracket 79 attached to the slide 60. The cam 64 is attached to the cam shaft 52 and rotates with it. A counterbalance weight 67 is attached to the cam lever 66 by a chain 69 running over a pulley 73 free to turn on a pin 75 attached to a bracket 77 fastened to the underside of the platen 47.

The bottle supporting and elevating member 10 is formed with downwardly extending sides 16, 18 to form side guides for the empty bottles being conveyed into the machine on the incoming conveyer belt 20 and also for the filled bottles leaving the machine on the outgoing conveyer. Provision is made for automatically moving the bottle supporting and elevating member 10 at predetermined times in the cycle of operation of the machine in order to elevate the bottles to purging and filling position and to subsequently lower the member 10 to a position flush with the incoming belt 20 and discharge belt 21, and for this purpose the member 10 is rigidly attached to slide members 80 by means of brackets 81. The slide members 80 are guided in slideways formed in brackets 82 supported by the platen 47 above referred to. The bottle supporting and elevating member 10 is actuated by a cam 84 fast on the cam shaft 52 by connections between it and the cam including a lever 86 fast on the rock shaft 50 and including a cam lever 88 also fast on the rock shaft 50 and which is provided with a cam roll 92 operating in the path 94 of the elevating cam 84. During the operation of the machine, when the bottle supporting and elevating member 10 is in its lower position, the bottle pushing bar 58 operates to push a row of empty bottles from the incoming conveyer belt 20 into a position upon the bottle supporting member 10 under the purging nozzle units 12, and this operation pushes over the row of previously purged bottles into a position beneath the filling nozzle units 14 and at the same time the row of previously filled bottles are pushed

laterally from the bottle supporting and elevating member onto the outgoing conveyer belt 21 to be discharged from the machine.

At each cycle in the operation of the machine, as the bottle supporting member is elevated, two rows of bottles are lifted until the mouth of each bottle in each row contacts and makes a tight seal with one of the series of purging nozzle units 12 and filling nozzle units 14 respectively.

In order to effect purging of the row of bottles in engagement with the purging nozzle units 12, provision is made for first evacuating the bottles to remove most of the air therefrom, and as herein shown, each purging nozzle unit 12 comprises a nozzle block 109 carried by a rod 102 supported in a bracket 104 which is adjustably secured to an elongated bar 106 mounted on a bracket 108 attached to the upright frame portions 24 of the machine. The lower end of the block 109 is provided with a sealing collar 112 which may be of flexible material, such as rubber or the like, arranged for sealing engagement with the top of the bottle.

The bracket 104 is provided with spaced bearing arms and a spring 107 coiled about the rod 102 and interposed between a collar 109 fast on the rod 102. The upper arm 111 of the bracket 104 is provided to permit the purging nozzle unit 12 to yield slightly when the mouth of the bottle engages its sealing collar 112 whereby to provide a firm seal. The sealing collar 112 is mounted on the lower end of a tubular member 114 fixed in the block and provided with a central opening 116 having lateral passageways 118 communicating with a chamber 120 formed in the block which in turn communicates with passageways 112 in a check valve 124 connected by a flexible tube 126 to a vacuum manifold 128. The vacuum manifold 128 extends longitudinally of the machine and is provided with a plurality of individual tubes 126 for connection to the series of individual nozzle blocks 109. As diagrammatically indicated in Fig. 16, the manifold represented at 128 is connected to a vacuum control valve 130 which in turn is connected by a pipe 132 to a vacuum tank 134 and vacuum pump 136 provided with a conventional relief valve 133 diagrammatically indicated in Fig. 16. In operation, the vacuum control valve 130 is arranged to be opened to effect evacuation of the bottles immediately after the supporting member 10 is elevated to present the bottles into sealing engagement with the nozzle units, the valve 130 being pneumatically actuated by a cam operated pilot valve 138 included in a compressed air line 140 connected by a supply pipe 142, as shown in Fig. 16, to any usual or preferred source of compressed air.

As illustrated in detail in Figs. 11 and 12, the vacuum control valve 130 comprises a housing 144 having a lower chamber 146 communicating with the vacuum manifold 128 and having an intermediate chamber 148 communicating with the vacuum supply pipe 132. A spring pressed valve member 152 arranged to seat against a shouldered portion of the housing between the chambers 146, 148 is arranged to cut off the vacuum to the manifold 128. As herein shown, the valve member 152 is provided with a depending stem portion 154 slidably fitted into a bore in a lower cap member 156 and is provided with an upright stem 158 slidably received in an upper cap member 160. The spring 164 aided by the vacuum normally maintains the valve member 152 in its closed position, as shown in Fig. 11, at which time the lower chamber 146 is open to the atmosphere through passageways 166 and atmospheric opening 168 in the cap member 156. An upper chamber 170 formed in the cap member 160 is arranged to slidably receive a plunger 172 which is normally retained in engagement with the stem 158 of the valve member by a spring 174 extended between the plunger and an outer cap member 176. The chamber 170 is connected by a pipe line 178 leading to the pilot valve 138, and as shown in detail in Fig. 9, the

pilot valve is provided with a spring pressed plunger 180 slidably mounted therein, the pipe 178 communicating with an intermediate chamber 182 surrounding the stem 181 of the plunger. The supply pipe 140 communicates with a lower chamber 186 through a passageway 188, and an upper chamber 185 communicates with an atmospheric opening 187. The plunger 180 is provided with enlarged diameter portions 190, 192 arranged to seat against shouldered portions 194, 196 of the chambers 185, 186 respectively. Normally, the plunger 180 is held in its upper position by the spring 183, as shown in Fig. 9, to cut off the supply of compressed air from the pipe 140 leading to the chamber 182, and at this time the line 178 is open to the atmosphere through chamber 185 and opening 187 so that the vacuum control valve 130 will normally remain in its upper or closed position under the influence of the spring 164 as shown in Fig. 11 and against the urging of the relatively weaker spring 174 of the pneumatically operated plunger 172. When the plunger 180 is depressed from its closed position to the open position shown in Fig. 10, compressed air is permitted to flow through the passageway 188, lower chamber 186, intermediate chamber 182 and passageway 191 to the pipe 178 leading to the vacuum control valve 130, and the compressed air entering the chamber 170 effects depression of the plunger 172 to open the valve 152 to the position shown in Fig. 12, thereby closing the atmospheric opening 168 and permitting communication between the vacuum supply pipe 132 and the vacuum manifold 128. As illustrated in Fig. 5, the pilot valve 138 is arranged to be opened in timed relation to the elevation of the bottle supporting member 10 by a cam 200 fast on the cam shaft 52 which cooperates with a roller 202 carried by one arm 204 of a lever pivotally mounted at 206. As shown in Fig. 4, a second arm 208 of the lever is provided with a spring 210 arranged to maintain the roller against its cam, and a third arm 212 is provided with a stud 214 arranged to engage the plunger 180 of the pilot valve.

In practice the evacuating operation is performed in a relatively short time in the cycle of operation, as indicated in the cam diagram, Fig. 15, and when the evacuation of the bottles is completed, the cam 200 effects closing of the pilot valve 138 to permit the vacuum control valve 130 to discontinue the vacuum to the manifold 128. It will be observed that the vacuum check valve 124 associated with each purging nozzle unit 12 is provided with a check ball 192 arranged to seat in an opening in the passageway 122 by gravity, as shown in Fig. 2, and when the vacuum is applied the ball will rise, as shown in Fig. 3, to permit communication between the vacuum lines and the bottles. Conversely, when the vacuum is discontinued, the ball will fall into its seat to maintain the vacuum in the bottles until the purging operation is initiated.

From the description thus far it will be seen that in the operation of the machine as soon as the bottle supporting member has been elevated, the cam 200 actuates the pilot valve 138 to effect opening of the vacuum control valve 130 and evacuation of the bottles, whereupon the valve 130 is closed to discontinue the vacuum to the manifold 128. Thereafter, provision is made for introducing an inert gas into the evacuated bottles, and as illustrated in Fig. 16, the inert gas may be controlled by an inert gas or purging valve 216 connected to a supply of inert gas by a pipe line 218 and having a pipe connection 220 to the inert gas manifold 222. As shown in Fig. 1, the inert gas manifold 222 is provided with a plurality of flexible tube connections 270 which are connected by pipe nipples 272 extended from each nozzle block 100, and as illustrated in Fig. 2, each nipple communicates with a chamber 274 and with a tube 276 carried by an adapter 278 fitted within the block 100. The tube 276 extends through the central opening 116 to a point below the sealing collar 112 and into the neck of

the bottle as shown in Fig. 2. The purging valve 216 is also arranged to be pneumatically controlled by a cam operated pilot valve 224 which may be similar to the pilot valve 138 and which is included in a compressed air line 226 connected to the main supply line 142 as shown in Fig. 16. Also connected in the pipe line 226 is a normally open clutch actuated pilot valve 260 to be described, and as illustrated in detail in Fig. 7, the inert gas valve is provided with a valve member 228 slidably mounted therein, one portion 230 of the valve being arranged to cut off ports 232 between the supply line 218 and the connecting pipe 220 to the manifold when in its closed position, as shown in Fig. 7, and when the valve member is in its open position, as shown in Fig. 8, the gas may flow through the ports 232 and annular groove 234 into a chamber 236 defined by the valve portions 230, 231, the chamber communicating with the connecting pipe 220 through ports 238 and annular groove 240. As illustrated in Fig. 7, the valve member 228 is normally maintained in its closed position by a spring 242 and is arranged to be pneumatically operated by a spring pressed plunger 244 slidably mounted in a chamber 245 in the valve and arranged to engage the end of the valve member 228. The chamber 245 is connected by a pipe 247 to the pilot valve 260 and, as shown in Fig. 16, the pilot valve 224 is provided with a plunger 246 which, as shown in Fig. 5, is arranged to be depressed by a cam 248 fast on the cam shaft 52 through connections including a roller 250 carried by a lever 252 also pivotally mounted at 206, the lever being provided with a stud 254 for engagement with the plunger 246.

In the operation of the machine as soon as the bottles have been evacuated and the vacuum has been cut off, the cam 248 actuates the pilot valve 224 to effect opening of the purging valve 216, whereupon the inert gas may flow into the manifold 222 to be drawn into the evacuated bottles to effect purging thereof. In practice the inert gas may and preferably will be under a pressure slightly above atmospheric pressure, and when the pressure of the inert gas in the containers reaches atmospheric pressure the surplus gas may escape through the passageways 122 and 194 of the ball check valve 124 into the vacuum manifold 128, the vacuum being discontinued at this time.

As indicated in Fig. 16, the second pilot valve 260 may be connected in the compressed air line between pipes 226, 247 and is arranged to be actuated by a control bar 262 operatively connected by a link 264 to the clutch lever 266 of the machine. The control bar 262 is arranged to engage and depress a plunger 268 of the pilot valve 260 when the clutch is thrown in to start operation of the machine so that in operation the pilot valve 260 is normally open. The pilot valve 260 is provided as a safety feature so that in the event the clutch is thrown out by rocking the clutch lever to the right, as viewed in Fig. 16, during the purging operation, the normally depressed plunger 268 of the pilot valve 260 is permitted to rise into the notch 263 formed in the bar 262 under the influence of the spring contained in the pilot valve to cut off the supply of compressed air and permit the purging valve 216 to be closed, thereby preventing the escape of inert gas when the machine is shut down.

Upon introduction of the inert gas into the previously evacuated bottles the purging valve 216 is closed by the cam 248, and the supporting member 10 is lowered to bring the bottles in line with the incoming and discharge conveyors. As illustrated in Fig. 1, when the supporting member 10 is initially elevated, the necks of the bottles are guided into openings formed in a guide bar 280, a plurality of which are adjustably mounted on horizontal rods 282 which are supported and slidably movable as a unit on vertical rods 284 depending from the underside of the bracket 108. Thus, at the end of the purging and filling operations the guide bars 280 follow the bottles

down to come to rest on collars 281 on the ends of the vertical rods 284, as shown in Fig. 1.

In a modified form of control for the purging operation the bottles may be alternately subjected to evacuating and purging operations whereby to provide a reversal of operation a predetermined number of times during the cycle of operation sufficient to completely purge the bottles whereby to reduce the air content to a minimum, the final portion of operation prior to separation of the bottles from the purging nozzle units 12 preferably being the admission of inert gas into the evacuated bottles. Successive reversals of operation, as described, cause flushing and diluting of the air in the bottles with the inert gas so that in practice the completely purged bottles are substantially devoid of air. Since the inert gas will be substantially at atmospheric pressure, it will not tend to escape from the bottles when separated from the purging nozzle units 12. As illustrated in Fig. 18, the cams for performing successive reversals of operation may include a vacuum control valve cam 283 and a purging cam 285 which may be substituted for the cams 200, 248 respectively and which, as illustrated, are provided with high and low spots arranged to open and close their respective valves in succession as described, through their respective pilot valves 138, 224 and connecting linkages.

While the apparatus thus far described may be used with advantage as a purging apparatus, it is preferred to incorporate it in a unitary combination purging and filling apparatus, and as herein shown, the filling nozzle units 14, which are arranged parallel to the purging nozzle units 12, as shown in Figs. 1 and 2, are each slidably mounted in a bracket 300 attached to a longitudinal bar 302 supported by the bracket 108 attached to the upright frames 24 resting on and fastened to the platen 47 of the machine frame. A spring 304 encircling a stem 306 of each filling nozzle unit 14 is provided to allow the filling nozzle to yield slightly as the mouth of the bottle comes in contact with the rubber collar 308 on the bottom of each nozzle. The lower end of the spring 304 rests on a collar 310 fast on the stem 306 of the nozzle, and the upper end of the spring bears against the upper bearing of the bracket 300. Thus, it will be seen that if a bottle should be out of proper alignment with a nozzle when the elevator is raised and any one of the nozzles should strike the top edge of the bottle, the spring 304 would yield and thus prevent breakage of the bottle.

As above described, in the operation of the illustrated machine provision is made for effecting the operation of the bottle filling mechanism to fill the row of previously purged bottles simultaneously with the purging of the row of bottles under the purging nozzle units 12, and while any filling mechanism may be employed, we prefer to effect the filling of the bottles by mechanism constructed and operating in accordance with the United States patent to Pennock, No. 1,737,677, to which reference may be made. For the purpose of understanding the present invention it is thought sufficient to state that the bottles are filled by the well known vacuum principle as clearly set forth in said Pennock patent. The liquid with which the bottles are to be filled is contained in a tank 312 located at the back of the machine and below the level of the bottles to be filled. The liquid is drawn by vacuum created in the bottle through a suction pipe 314, one end of which is immersed in the liquid of the tank, the other end of which is connected to the filling nozzle units 14 at a nipple 316. A suction pump, indicated generally at 318 in Fig. 17 and of well known construction, is connected through novel control mechanism to be described to a pipe 320 which leads into and has an opening at the top of an inverted bowl 322. A vacuum is created in the bowl 322 by the suction pump, and when the mouth of the bottle is sealed by the rubber collar 308, as shown in Fig. 1, the vacuum in the bowl operates through a check valve 324, a manifold pipe 326, flexible tubing 328 and a passageway 330 extending down through the filling nozzle unit 14 into the inside of the bottle to evacuate the bottle. The suction of the bottle is connected with the suction pipe 314 by a tubular member 332 positioned concentrically inside of an outer tube 334, and the passageway through this tube 332 is connected with a chamber 336 of the filling nozzle unit 14 which in turn is connected with the suction pipe 314.

When the air is exhausted from the bottle to be filled, the liquid in the tank 312 will be caused to flow through the suction pipe 314 through the chamber 336 and through the tube 332 into the bottle. When the bottle is filled so that the liquid reaches the bottom of filling tube 332, the suction from the vacuum pump draws off any further liquid coming into the bottle through the annular passageway between tubes 332, 334 into chamber 330 and through flexible tube 328 and manifold 326 into the bowl 322, and the surplus liquid may subsequently be returned to the tank 312 by gravity, thus filling all bottles to the same height.

It will be observed that the filling operation automatically commences when the elevator 10 lifts the bottles to filling position and is completed before the elevator again descends. When the elevator 10 descends and the contact is broken between the rubber collar 308 and the mouth of the bottle, the suction in the bottle is broken and the flow of liquid from the tank 312 through the filling nozzle units 14 is terminated. Any surplus liquid that is drawn into the bowl 322 finds its way back to the tank 312 through a drain pipe 340 which is provided on its end with a check valve 342 for preventing the flow of liquid through this pipe when the bowl 322 is under vacuum. As illustrated in Fig. 17, two bowls 322, 323 may be used, and the suction line from the vacuum pump 318 may be connected through a cam operated slide valve, indicated generally at 344, designed to operate periodically to release the vacuum on the bowls alternately, as clearly set forth in the Pennock patent, No. 1,737,677.

In the operation of the vacuum filling mechanism thus far described the inert gas evacuated from the bottles is replaced by the liquid during the filling operation, and when a predetermined filling level is reached, surplus liquid is drawn into the inverted bowls 322, 323 to be returned to the supply tank 312, as above described. As illustrated in dot and dash lines in Fig. 1, the entire upper portion of the machine is provided with a hood 500 substantially enclosing the purging and filling mechanisms and the intake and discharge conveyors 20, 21, and the interior of the hood is continuously charged with nitrogen gas from a supply thereof through one or more nozzles 502 whereby to provide an atmosphere of nitrogen gas about the bottles slightly above atmospheric pressure during the conveying, purging and filling operations, thus preventing air from entering the open mouths of the purged bottles when being moved from the purging to the filling station and when being moved from the filling station to the discharge conveyor. In practice the hood charged with nitrogen gas may be extended along the discharge conveyor to prevent air from entering the open mouths of the containers during their progress to a subsequent machine for applying closures to the containers whereby to provide a filled and closed container substantially devoid of air. In practice in the conventional filling machines the suction is usually continued at the same rate after the seal is broken between the filling nozzle units 14 and the containers in order to prevent gravitational drip of the liquid from the nozzles. However, in accordance with another feature of the present invention provision is made for substantially reducing the suction at this time to a point sufficient to prevent drip from the nozzles and yet such as to prevent excessive withdrawal of the inert gas from the interior of the hood 500 whereby to maintain a protective atmosphere of inert gas around the containers and to prevent air from being drawn into the interior of the hood. As shown in the piping diagram, Fig. 17, this may be accomplished by including a vacuum

control valve 400 in the suction line between the vacuum pump 318 and the cam operated slide valve 344, and also a by-pass line having a manually operated pressure regulator 402 connected between the main vacuum line 405 and the pipe line 404 by pipes 406, 408. The vacuum control valve 400 is arranged to be pneumatically operated by a cam operated pilot valve 410 which may be similar to the pilot valve 138 shown in Fig. 9. As illustrated in detail in Figs. 13 and 14, the vacuum control valve may include a housing 414 having an upper chamber 416 which communicates with the pipe line 404, and an intermediate chamber 418 which communicates with the pipe line 419 connected to the main supply line 405. A valve member 420 is arranged to seat in a shouldered portion 422 between the chambers 416, 418 to cut off the suction between the pipes 419, 404, the valve member having an upright stem portion 421 which is guided in an upper cap member 424 and a depending stem portion 423 arranged to cooperate with a pneumatically operated plunger 426 slidably mounted in a cap member 425 secured to the lower end of the housing 414. The valve member 420 is normally urged into an open position, as shown in Fig. 14, by a spring 428. The plunger 426 operates in a chamber 430 and is normally urged into engagement with the depending stem 423 of the valve member 420 by a relatively weaker spring 432. Referring now to Fig. 17, the chamber 430 of the valve 400 is connected by a pipe 434 to the outlet of the pilot valve 410, the inlet of the pilot valve being connected by a pipe 436 to any usual or preferred supply of compressed air. The pilot valve 410 is provided with a plunger 438 which is arranged to be depressed to open the pilot valve during or immediately after the seal is broken between the filling nozzle units 14 and the bottles. As illustrated in Fig. 5, this may be accomplished by a cam 440 fast on the cam shaft 52 and which cooperates with a roller 442 carried by a lever 444 pivotally mounted at 446. As shown in Fig. 4, a second arm 448 of the lever is provided with a spring 450 for holding the roll against its cam, and a third arm 452 is provided with a stud 454 for engagement with the plunger 438. The suction line 419 may be provided with a conventional relief valve 456, as illustrated in Fig. 17. Thus, in practice when the filling operation is completed and the seal is broken the vacuum control valve 400 is closed, thereby cutting off the suction through the control valve 400, the suction being continued at a reduced rate through the by-pass pipe line 406, the pressure regulator 402 and pipe line 408 to the main supply line 405. Thus, in operation the suction through the filling nozzle tubes 334 is reduced at the end of the filling operation to prevent excessive withdrawal of the inert gas from the hood. After the bottles have been purged and filled in the manner described and the elevator 10 has moved to its lower position, the filled bottles are ejected onto the outgoing belt 21 by the movement of the next and previously purged row in position beneath the filling nozzles. As previously described, the contents of the filled bottles are protected from the air by an atmosphere of nitrogen gas introduced into the hooded portions during the discharge and conveyance of the bottles to subsequent machines for the application of closures thereto, thus preventing air from entering the space above the level of the liquid in the filled bottles during such conveyance and until the closure is applied.

From the above description it will be observed that the present unitary purging and filling machine is adapted to evacuate a row of containers to remove most of the air therefrom and to then admit an inert gas into the bottles to mix with and dilute any air remaining in the bottles after evacuation thereof whereupon the bottles are vacuum filled in a manner such as to provide a filled container substantially devoid of air. In this manner the oxygen content of the filled bottles is reduced to a minimum whereby to prevent oxidation of those bottled or pack-

aged food products which are particularly susceptible to contamination upon exposure to the air.

It will also be observed that the above described manner of purging and filling containers by first evacuating the air in the container and then introducing an inert gas therein effects a substantial economy in the use of such gas. That is, by merely replacing with inert gas the air evacuated from the container while the mouth of the container is in sealed engagement with the evacuating and purging apparatus, a much smaller volume of gas is required as compared with prior purging apparatus wherein a stream of inert gas is blown into the open mouth of a container to mix with and dilute the air therein. Also, by reducing the suction of the vacuum filling nozzles during the time the latter are disengaged from the containers, a substantial economy in the use of the gas within the hooded portion is effected.

While the preferred embodiment of the invention has been herein illustrated and described it will be understood that the invention may be embodied in other forms within the scope of the following claims.

Having thus described the invention, what is claimed is:

1. In a machine of the character described, in combination, two laterally spaced nozzles for cooperation with separate containers, container supporting means for supporting two containers, each in operative position and sealing engagement with relation to one of said nozzles, one of said nozzles constituting a purging nozzle and being operatively connected to a source of suction and to a source of inert gas, control means for controlling the application of suction through said purging nozzle to a container cooperating therewith and for controlling the flow of inert gas into the container through said purging nozzle, means for operating said control means to first evacuate the air from the container disposed in operative position with respect to said purging nozzle and for thereafter introducing inert gas through said nozzle into the container thus evacuated while maintained in said sealing engagement, means for removing the thus purged container from said sealing engagement into operative sealing engagement with the second nozzle, means for thereafter filling the container with a liquid through said second nozzle and means enclosing said nozzles and containers in an atmosphere of inert gas at a pressure slightly above atmospheric pressure during said purging and filling operations.

2. In a machine of the character described, in combination, a purging nozzle, container supporting means for supporting a container in operative position and sealing engagement with relation to said purging nozzle, said purging nozzle being operatively connected to a source of suction and to a source of inert gas, control means for controlling the application of suction through the nozzle to the container and the flow of inert gas into the container through said nozzle, means for operating the control means to first evacuate the container and then introduce inert gas therein while remaining in said sealed engagement with the purging nozzle, container filling mechanism including a second nozzle spaced from said first nozzle for subsequently filling the purged container, and means for maintaining said nozzle and filling mechanism in an atmosphere of inert gas at slightly above atmospheric pressure during said purging and filling operations.

3. In apparatus of the character described, in combination, container supporting means for supporting two containers, laterally spaced container purging mechanism and container filling mechanism, each provided with a nozzle for sealing engagement with one of said containers, said purging nozzle being operatively connected to a source of vacuum and a source of inert gas, means for controlling the flow of air and gas through said purging nozzle to first evacuate air from the container and to then admit inert gas into the container while maintained in said sealing engagement to reduce to a minimum the air content of the container prior to the filling operation,

means for thereafter removing the container from said sealed engagement and for moving the purged container laterally and into operative sealing engagement with the filling nozzle to be filled, and means for maintaining said nozzles in an atmosphere of an inert gas slightly above atmospheric pressure to prevent air from entering the purged containers upon separation from sealing engagement with their respective purging and filling mechanisms, whereby to produce a filled container substantially free of air.

4. In a machine of the character described, in combination, a purging nozzle, container supporting means for supporting a container in operative position and sealing engagement with relation to said purging nozzle, said purging nozzle being operatively connected to a source of suction and to a source of inert gas, control means for controlling the application of suction through the nozzle to the container and the flow of inert gas into the container through said nozzle, means for operating the control means to first evacuate the container and then introduce inert gas therein while being maintained in said sealed engagement to enable said container to be subsequently filled with minimum air therein, and means including a vacuum filling nozzle spaced laterally from said purging nozzle for subsequently filling the container.

5. In apparatus of the character described, in combination, laterally spaced container purging mechanism and container vacuum filling mechanism, each provided with a nozzle for sealing engagement with a container, said purging nozzle having a suction opening and an inert gas opening each in communication with the interior of a container, a source of vacuum and a source of inert gas operatively connected with said openings, means for controlling the flow of air and gas to first create a vacuum in the container to evacuate the air therein and to then admit inert gas into the container while maintained in said sealing engagement to reduce to a minimum the air content of the container prior to the vacuum filling operation whereby to produce a filled container substantially devoid of air.

6. In apparatus of the character described, in combination, laterally spaced container purging mechanism and container filling mechanism, each provided with a nozzle for sealing engagement with a container, said purging nozzle having a suction opening and an inert gas opening for communication with the interior of the container, a source of vacuum and a source of inert gas operatively connected with said openings, valve means controlling the flow of said air and gas, means for actuating said valve means to first create a vacuum in the container to remove most of the air therefrom and then admit inert gas into the container to mix with and dilute any remaining air in the container while maintained in said sealing engagement to reduce to a minimum the air content of the container prior to the filling operation, and means for thereafter removing the container from said sealing engagement and for moving the purged container laterally and into operative sealing engagement with the filling nozzle to be filled whereby to produce a filled container substantially devoid of air.

7. The method of filling a container with a liquid comprising the steps of first evacuating the container, then admitting an inert gas into the evacuated container while being maintained in sealing engagement with one nozzle, removing the container from said sealing engagement and filling the container with a liquid through a second nozzle, said evacuating and filling operations being conducted in an atmosphere of an inert gas slightly above atmospheric pressure.

8. The method of filling a container with a liquid which consists in first moving the container into sealing engagement with a nozzle, then applying suction to the nozzle to evacuate the container, then discontinuing the suction and introducing an inert gas into the evacuated container while maintaining it in sealed engagement with

the nozzle, removing the container from said sealed engagement and then moving the container into sealing engagement with a second nozzle and withdrawing the inert gas from the container and filling the container with liquid through said second nozzle.

9. In apparatus of the character described, in combination, container purging mechanism and container filling mechanism, each provided with a nozzle for sealing engagement with a container, said purging nozzle having a suction opening and an inert gas opening for communication with the interior of the container, a source of vacuum and a source of inert gas operatively connected with said openings, valve means controlling the flow of said air and gas, means for actuating said valve means to first create a vacuum in the container to remove most of the air therefrom and then admit inert gas into the container to mix with and dilute any remaining air in the container to reduce to a minimum the air content of the container prior to the filling operation, means for thereafter moving the purged container into operative engagement with the filling nozzle to be filled whereby to produce a filled container substantially devoid of air, and a check valve associated with the purging nozzle adapted to close said suction opening upon discontinuance of the vacuum whereby to maintain the vacuum in the container until the inert gas is admitted.

10. In apparatus of the character described, in combination, container purging mechanism and container filling mechanism, each provided with a nozzle for sealing engagement with a container, said purging nozzle having a suction opening and an inert gas opening for communication with the interior of the container, a source of vacuum and a source of inert gas operatively connected with said openings, valve means controlling the flow of said air and gas, means for actuating said valve means to first create a vacuum in the container to remove most of the air therefrom and then admit inert gas into the container to mix with and dilute any remaining air in the container to reduce to a minimum the air content of the container prior to the filling operation, and means for thereafter moving the purged container into operative engagement with the filling nozzle to be filled whereby to produce a filled container substantially devoid of air, said means for actuating said valve means including individual cam operated pilot valves operatively connected to the air and gas valves.

11. In apparatus of the character described, in combination, container purging mechanism and container filling mechanism, each provided with a nozzle for sealing engagement with a container, said purging nozzle having a suction opening and an inert gas opening for communication with the interior of the container, a source of vacuum and a source of inert gas operatively connected with said openings, valve means controlling the flow of said air and gas, means for actuating said valve means to first create a vacuum in the container to remove most of the air therefrom and then admit inert gas into the container to mix with and dilute any remaining air in the container to reduce to a minimum the air content of the container prior to the filling operation, and means for thereafter moving the purged container into operative engagement with the filling nozzle to be filled whereby to produce a filled container substantially devoid of air, said valve actuating means being arranged to alternately create a vacuum in the container and admit gas therein a plurality of times during the purging operation.

12. In a machine of the character described, in combination, two nozzles for cooperation with separate containers, container supporting means for supporting two containers, each in operative position with relation to one of said nozzles, one of said nozzles constituting a purging nozzle and being operatively connected to a source of suction and to a source of inert gas, control means for controlling the application of suction through said nozzle to a container cooperating therewith and for controlling

the flow of inert gas into the container through said nozzle, means for operating said control means to first evacuate the air from the container disposed in operative position with respect to said purging nozzle and for thereafter introducing inert gas through said nozzle into the container thus evacuated, means for moving the thus purged container into operative engagement with the second nozzle, means for thereafter filling the container with a liquid through said second nozzle, and means enclosing said nozzles and containers in an atmosphere of inert gas at a pressure slightly above atmospheric pressure during said purging and filling operations, said filling operation being by vacuum, and means for continuing the vacuum at a reduced rate at the end of the filling operation.

13. In apparatus of the character described, in combination, container purging mechanism and container filling mechanism, each provided with a nozzle for sealing engagement with a container, said purging nozzle having a suction opening and an inert gas opening for communication with the interior of the container, a source of vacuum and a source of inert gas operatively connected with said openings, valve means controlling the flow of said air and gas, means for actuating said valve means to first create a vacuum in the container to remove most of the air therefrom and then admit inert gas into the con- 25

tainer to mix with and dilute any remaining air in the container to reduce to a minimum the air content of the container prior to the filling operation, means for thereafter moving the purged container into operative engagement with the filling nozzle to be filled whereby to produce a filled container substantially devoid of air, said means for actuating said valve means including individual cam operated pilot valves operatively connected to the air and gas valves, driving means and a clutch controlling said driving means, a second pilot valve operatively connected with said gas valve arranged to be opened when the clutch is engaged and to be closed when the clutch is disengaged whereby to prevent escape of gas in the event the operation of the machine is discontinued during the purging operation.
